MAT

James A. Beard, Jr., Mishawaka, Ind.

Application February 12, 1934, Serial No. 710,959

3 Claims. (Cl. 248—22)

This invention relates to floor coverings and particularly to mats adapted to be used under the legs of washing machines and other household devices which are susceptible to creeping or movement away from a predetermined set position.

The principal object of my invention is to provide a mat so formed that the washing machine can be readily moved thereon and then retained against shifting or creeping on the floor.

10 A further object is to provide a mat formed principally of rubber having pockets therein adapted to receive the casters on the bottoms of the legs of a washing machine or other household device to prevent such machine from moving away from a predetermined set position.

15 A further object is to provide a molded rubber mat having portions formed to receive the casters mounted on washing machines and the like, and a relatively thin central portion connecting the 20 caster-receiving portions.

Another object is to provide a molded rubber mat having caster-receiving portions formed with relatively thin outwardly extending edges and caster-receiving pockets therein, the walls of the 25 pockets tapering outwardly to the edges.

Another object is to provide a molded rubber mat having caster-receiving pockets formed therein, the walls of the pockets being shaped to snugly fit the peripheries of the respective casters.

30 The above being among the objects of the present invention, the same consists of certain details of manufacture and construction, which will be apparent from the drawing and the detailed description to follow, the same being for the purpose 35 of illustration only and not as limiting the scope of the invention, the scope of which is to be measured entirely by the subjoined claims.

In the drawing in which like numerals refer to like parts throughout the several views,

40 Fig. 1 is a plan view of a mat having my invention incorporated therein adapted to support a washing machine having four legs.

Fig. 2 is a plan view similar to Fig. 1, showing a mat formed for a washing machine having three 45 legs.

Fig. 3 is an enlarged fragmentary sectional view taken on the lines 3—3 of Figs. 1 and 2, the thickness of the mat being somewhat distorted to better illustrate my invention.

50 Fig. 4 is an enlarged sectional view taken on the lines 4—4 of Figs. 1 and 2, the thickness of the mat being also distorted in this view to better illustrate the invention.

Fig. 5 is a fragmentary sectional view taken on 55 the lines 5—5 of Figs. 1 and 2, showing the body

portion of the mat, the thickness being somewhat distorted.

Fig. 6 is a plan view of a mat showing a slightly modified form of my invention.

Fig. 7 is a sectional view taken on the line 7—7 of Fig. 6, showing the shape longitudinally of one of the caster receiving pockets.

Fig. 8 is an enlarged transverse sectional view taken on the line 8—8 of Fig. 6, the same being substantially at a right angle to Fig. 7.

Fig. 9 is an enlarged fragmentary sectional view taken on the line 9—9 of Fig. 6, showing the shape of the mat intermediate the caster-receiving pockets.

In power-driven washing machines and other household articles, considerable annoyance and difficulty has been encountered due to the device creeping or moving away from a predetermined set position. As such devices are usually used in basements where the floor is not perfectly level, the tendency for such devices to move about due to vibration set up in the machine is greatly increased often making it necessary to provide blocks or wedges beneath the casters to prevent such movement. I have eliminated the difficulties heretofore encountered by providing a mat having caster-receiving pockets formed therein into which a machine can be moved with relative ease and which will support the machine against creeping or slipping even if the floor is not level.

Referring to the drawing in detail and particularly to Figs. 1 to 5 inclusive, I have provided a mat indicated generally by the numeral 10 and having a body or web portion 11 and caster-receiving portions 12. As such mats are usually made from molded rubber, the body or web portion 11 is preferably thicker at the center thereof than at the edges, as is illustrated in Fig. 5. Although, if desired, it can be made of uniform thickness.

At the extremities of the body or web portion 11 are caster-receiving portions 12 formed integrally therewith and which have pockets 13 therein bounded by walls 14 generally triangular in cross-section and tapering out to the relatively thin exposed edges 15, as shown in Figs. 3 and 4. If desired, a bead 16 may be formed on the mat in spaced relation to the pockets 13, as is clearly shown in Figs. 1, 2 and 3, these beads preferably fading out at 16' to permit forming of the relatively thin exposed edges 15 along the sides and end of the portion 12, as is best shown in Figs. 1 and 2.

The pockets 13 are formed to receive casters

17, one of which is indicated in dotted lines in Fig. 4. As the casters now used on washing machines and other household devices are of about the same diameter, the size or proportion 5 of the receiving pockets 13 need not vary to any great extent to accommodate different makes of machines and the walls 14 thereof are preferably formed to snugly fit against the periphery of the casters, as is clearly shown in Fig. 4. That 10 is, the walls are preferably formed to engage with the face of the caster, while the bottom of the caster is spaced slightly from the bottom of the pocket 13. Due to the weight of the machine the casters will settle into the pockets so 15 that the walls 14 will firmly grip the casters to prevent any movement of the machine relative to the mat. There is, however, some difference in the spacing of the legs on various makes of machines and I, therefore, prefer to elongate the 20 pockets 13, as is clearly shown in Figs. 1, 2 and 3, to accommodate the different makes and sizes of machines. If desired, I may reinforce the mat with suitable reinforcing strips 18 which may 25 be of woven material or sheets of metal to thus maintain longer life of the mat where the casters contact therewith.

In moving the washing machine or other household device on to the mat, one of the casters 17 can be moved into the pocket 13 to the position shown in Fig. 4, which caster can then be 30 used as a pivot and the remaining casters rolled over the thin exposed edges 15 of the mat on to the walls 14 of the pocket and then into the pocket 13. When in this position, the weight 35 of the machine on the mat will be sufficient to cause the mat to grip against the floor and not slip or slide relative thereto and as the casters will not readily move out of the pockets, the machine is, therefore, maintained against creeping or moving 40 along the floor from the predetermined set position.

In Fig. 1, I have shown a mat suitable for use with a washing machine having four legs and in Fig. 2, I have shown a mat suitable for use with 45 such a machine having three legs. It, of course, will be readily understood to those skilled in the art that the mat can be made in various shapes and sizes to accommodate machines having any number of legs or spaced in any relation to each 50 other and thus my invention is not limited to the specific forms shown.

In Figs. 6 to 9 inclusive, I have shown a mat having the same general characteristics as the mat shown in the preceding figures but which 55 is preferably circular in shape and which has a body portion 20 having a bead 21 extending around the edge thereof, as shown in Fig. 6, which is useful in retaining any water on the mat which may drip from the machine. As illustrated, this mat also has caster-receiving pockets 22 formed with walls 23 generally triangular in cross-section and terminating in a relatively

thin edge 24 along the exposed edge face of the mat. Although, in Fig. 6 I have shown a mat suitable for use with a machine having four legs, it will be evident that a mat for a machine having more or less legs can be provided in the 5 same manner merely by the rearrangement of the pockets.

To better illustrate my invention, Figs. 3, 4, 5, 7, 8 and 9 have been somewhat distorted to show a greater thickness of material than would 10 probably be used in mats made by quantity production methods. It is, therefore, to be understood that my invention is not limited to the proportions shown as such mats may be made relatively thin if so desired or relatively thick 15 if it is desired to use a soft spongy rubber. It will also be recognized that in addition to providing a mat which will prevent creeping of the machine on the floor, that the same provides an insulator against electric shocks. It will also 20 be understood that the shape and design of the body portion of the mat can be modified to provide many different shapes.

While I have shown mats suitable for use with washing machines and other household devices having three and four legs, my invention is not to be limited to the structures shown but entirely by the scope of the appended claims.

What I claim is:

1. A mat for stabilizing a caster supported machine comprising a body of resilient material having a plurality of caster supporting portions, each caster supporting portion comprising a ridge surrounding a caster receiving depression and sloped from the top thereof to the edge of said 35 caster supporting portion to provide an inclined plane up which a caster may be rolled into said depression, the material of said mat being cut away between said caster receiving portions to render said inclined planes accessible to said 40 casters around the major part of the circumference of said depressions.

2. A mat for stabilizing a caster supported machine comprising a body of resilient material having a plurality of caster supporting portions 45 each comprising a ridge of triangular cross-section surrounding a caster receiving depression, said depressions being elongated along respective lines radiating from the center of said mat to accommodate said mat to machines of 50 varying dimensions.

3. A mat for stabilizing a caster supported machine comprising, a body of resilient material having elongated caster supporting portions therein, each comprising a ridge of triangular 55 cross-section at each side of a caster receiving depression, the width of the bases of said ridges being at least twice the height of said ridges to provide relatively long sloping side walls on each side of said ridges whereby the casters can 60 be easily rolled into and out of said depressions.
